UNITED STATES PATENT OFFICE.

JOHN R. CAZIER, OF NORTH EAST, PENNSYLVANIA.

IMPROVEMENT IN SAFETY-VALVES FOR STEAM-BOILERS.

Specification forming part of Letters Patent No. 128,851, dated July 9, 1872.

To all whom it may concern:

Be it known that I, JOHN R. CAZIER, of North East, in the county of Erie and State of Pennsylvania, have invented certain new and useful Improvements in "Safety-Valves for Steam-Boilers;" and do hereby declare the following to be a full, clear, and exact description thereof, reference being had to the accompanying drawing and to the letters of reference marked thereon.

My invention relates to the addition to steam safety-valves of an appendage by which, after the valve opens, the issuing steam shall have more power to lift the opposing weight or spring, and thus to escape more freely.

In order to enable others skilled in the art to which my invention appertains to make and use the same, I will now proceed to describe its construction and operation, referring to the annexed drawing, which forms a part of this specification, and in which—

Figure 1 is a transverse vertical section of a machine embodying my invention, the valve opening downward. Fig. 2 represents the principal parts detached or separated. Fig. 3 is a view similar to that shown in Fig. 1, except in the hinging of the valve-lever, and in the formation of the removable piece containing the valve-seat, so that the valve shall open upward instead of downward.

B represents the dome of a steam-boiler, and C the pipe turning downward, so that water condensing from steam generated in the boiler shall apply to the valve, as described and claimed in my patent No. 124,792, dated March 19, 1872. D is the valve, the face of which is similar to the ordinary form, but proportionally larger, extending outwardly past the valve-seat. The valve, in its largest horizontal circumference, is cylindrically formed, to match the short tube E, but so as to work easily up and down in it. The tube E ordinarily overlaps the valve-seat tube F. The extent to which it overlaps is regulated by the adjusting-screws G G in the yoke H, which is attached crosswise to the tube E at its lower end. A spring, I, which is banded to the graduating

lever J, presses upward against the yoke H, and thus keeps the tube E in its place. The spring is slotted, as shown in Fig. 2, to admit the valve-pin k, and also a short double-flanged tube to connect it with the yoke. Instead of this flanged tube, bent or notched pins a a may be attached to the yoke, as shown in Fig. 2, to engage the edge of the spring on either side. A cord, L, passing over pulleys b b, one at each end of the lever J, connects with the spring, which by it can be forced toward the lever, carrying the tube E with it. The valve-pin k hinges upon the valve-lever J, which has a poise at M and a fulcrum attached to the tube C. When the valve begins to part from its seat by the steam pressure against it, the issuing steam being much confined by the tube E, and now having a much larger surface of the valve to act upon, readily forces it from its seat till the tube E ceases to overlap the tube F, when the steam escapes with a freedom increased in proportion to the increase of valve surface upon which it now acts. But this increase in the power of the steam upon the valve will prevent the return of the latter to its seat when the boiler is sufficiently relieved. This difficulty is to be overcome by drawing the cord L, by which the tube E will be passed downward over the valve, allowing it to return readily.

The valve and its appendage and the valve-tube as described, may be made of other than circular form on their outer surfaces if desired. Instead of the spring I, a spiral spring, surrounding the valve-pin, may be employed, as seen at i, Fig. 2, the quadruple hook above the spring being designed to attach crosswise and permanently to the yoke H, when the spring can be connected by screwing it upon the lower extremities of the hook.

The valve-seat tube F must be of proper size in its inner diameter to screw to the tube C, and in its outer diameter to nearly fill the tube E when the latter passes over it. This last object can be accomplished by means of a shoulder, as at f, Fig. 2, to avoid excessive weight. The valve-tube F attaches by screw-

ing to the tube C, and can be readily unscrewed and removed. It may be variously modified. One modification is shown in Fig. 3.

Having thus fully described my invention, what I claim as new, and desire to secure by Letters Patent, is—

In combination with a safety-valve, an exterior tube, E, overlapping the valve-seat and

operated by means of a spring, substantially as and for the purposes herein set forth.

In testimony that I claim the foregoing, I have hereunto set my hand and seal this 1st day of April, 1872.
